(57) **CLAIM**

We claim the ornamental design for a transparent cake shield having candle apertures and handles, as shown and described.

DESCRIPTION

FIG. 1 is a perspective view of a transparent cake shield having candle apertures and handles showing our new design; the broken lines depict environmental structure for illustrative purposes only and form no part of the claimed design;

FIG. 2 is a front elevational view thereof, the rear elevational view being identical thereto;

FIG. 3 is a side elevational view thereof, the elevational view of the opposing side being identical thereto;

FIG. 4 is a top plan view thereof; and,

FIG. 5 is a bottom plan view thereof.
